Henry C. Egerton.

J. G. Roberts Atty

UNITED STATES PATENT OFFICE.

HENRY C. EGERTON, OF PASSAIC, NEW JERSEY, ASSIGNOR TO WESTERN ELECTRIC COMPANY, INCORPORATED, OF NEW YORK, N. Y., A CORPORATION OF NEW YORK.

TELEPHONE SET.

1,339,814.

Specification of Letters Patent. Patented May 11, 1920.

Application filed January 28, 1918. Serial No. 214,130.

To all whom it may concern:

Be it known that I, HENRY C. EGERTON, a citizen of the United States, residing at Passaic, in the county of Passaic and State 5 of New Jersey, have invented certain new and useful Improvements in Telephone Sets, of which the following is a full, clear, concise, and exact description.

The invention relates to a telephone set 10 and more particularly to a set of the loud-speaking or announcing type.

The set of the invention is particularly designed for use on naval vessels for transmitting orders, and especially for submarine vessels where the amount of space available to accommodate the telephone set is a minimum.

In accordance with a feature of the invention a set is provided in which a long 20 amplifying path is provided from the receiver in the form of a spirally formed horn which occupies a minimum amount of space.

In order to meet a condition imposed upon the set by the continuous vibration to which 25 it is subjected in service, in accordance with another feature of the invention, a face or mounting plate is provided with which the receiver horn and the transmitter mouthpiece are integral. The horn and transmitter mouthpiece form the sole supports 30 for the receiver and transmitter.

In the drawing, Figure 1 is a rear elevation of the set removed from the casing; Fig. 2 is a longitudinal sectional view 35 through the casing substantially on the line 2-2 of Fig. 1; and Fig. 3 is a transverse section substantially on the line 3-3 of Fig. 1.

The entire set, including transmitter and 40 receiver, is inclosed in a casing which may be of metal or other suitable material which, in the embodiment of the invention disclosed, takes the form of a rectangular box indicated at 1. This box or casing may 45 either be built into a partition or suitably secured thereto. Forming a cover for the casing is a cover plate indicated as a whole at 2, which plate is adapted to form a complete cover for the casing and to be attached 50 thereto in any suitable manner. Integral with the cover 2 and preferably cast integral therewith is a spiral receiver horn 3 and a transmitter mouthpiece 4. Supported solely by the mouthpiece 4 is a transmitter

5 which may be of any usual well-known type, which is provided on its casing with a projecting sleeve 6 adapted to engage threads in the mouthpiece 4. A loud-speaking receiver indicated at 7 is similarly attached to and supported solely by the inner end 8 of the spiral receiver horn. In order to provide a rigid construction the end 8 of the receiver horn is secured to the body of the horn by an integral web portion 15. The terminals 9 of the receiver 60 are connected to a terminal block 10, as are also the terminals 11 of the transmitter. The transmitter and receiver are associated with a suitable line circuit by means of conductors entering the casing through the tube 16. The conductors are also led through this tube to the terminals of a push button switch 12 which, when depressed, serves to connect the transmitter in operative relation with a source of potential. 75

The set is particularly adapted to be used in naval vessels and more particularly in submarine vessels, and consequently in order that the orders transmitted through such set may be audible above the noise incidental 80 to the operation of the machinery of the submarine vessel, an amplifying horn is essential for the receiver. It is also essential that the set as a whole should occupy a minimum amount of space as space is at a 85 premium in vessels of this character. The spiral horn of the invention as illustrated and described above provides a horn having a relatively long amplifying path and is one which occupies a minimum amount of space. 90 It will be readily apparent that the amplifying path of this spiral horn is considerably greater than the maximum diagonal dimension of the entire casing. The receiver horn and transmitter mouthpiece being formed integral with the mounting plate and being mounted with the transmitter and receiver respectively, a construction is provided in which there is a minimum number 95 of joints and consequently one which is affected only in a small degree by the vibration to which the set is ordinarily subjected in service. The whole construction is rigid and compact.

What is claimed is:

1. A telephone set comprising a receptacle, a cover for said receptacle, a sound-conducting horn, of substantially the form

of a conical helix, with its base secured to said cover, and a telephone instrument mounted on the apex of said horn.

2. A telephone set comprising a receptacle, a cover for said receptacle, a coiled sound-conducting horn having an expanded base secured to said cover and a constricted end connected by a web to said base, and a telephone instrument supported on said constricted end.

3. A telephone set comprising a receptacle, a cover, a coiled sound-conducting horn secured to said cover and substantially filling said receptacle, and a telephone instrument associated with said horn within 15 the receptacle.

In witness whereof I hereunto subscribe my name this 25th day of January, A. D. 1918.

HENRY C. EGERTON.
